SHUTTLE BOX

Carl D. Brown, Hopedale, Mass., assignor to
 Draper Corporation, Hopedale, Mass., a corporation of Maine

Application December 16, 1940, Serial No. 370,229

6 Claims. (Cl. 139—183)

The present invention pertains to fly shuttle looms, and more particularly relates to shuttle boxes for such looms.

Looms of the type mentioned commonly include a reciprocating lay on which is mounted a reed and a shuttle box. The shuttle box includes a back box plate having a shuttle guiding surface which must be accurately aligned with the reed in order that the shuttle may be properly picked into and out of the shuttle box.

Various constructions have been proposed for aligning the shuttle guiding surface with the reed. However, these constructions have either been too complicated and difficult to adjust or have not given the accuracy of alignment required.

Accordingly, it is a principal object of the present invention to provide in a loom having a lay on which is mounted a reed and a shuttle guiding member, a supporting member for the lay and means adjustably connecting the shuttle guiding member to the supporting member, said means comprising a plate positioned between the supporting member and the shuttle guiding member, threaded means adjustably connecting the plate to one of said members, for moving the shuttle guiding member transversely of the lay and tilting same about a horizontal axis extending longitudinally of the lay, and means for locking said shuttle guiding member to said supporting member in adjusted position.

The foregoing and other objects of the invention are accomplished in the construction illustrated on the accompanying drawing, of which:

Fig. 1 is a plan view of a lay beam, shuttle box and other parts of a loom to which the invention has been applied.

Fig. 2 is a horizontal section of certain parts of Fig. 1, this view being to a larger scale.

Fig. 3 is a front view of a portion of the lay beam and the inner end of the shuttle box, and

Fig. 4 is a section view taken on line 4—4 of Fig. 2, this view being to a larger scale.

The drawing shows but part of a loom having my invention applied thereto, the parts and mechanisms not shown being of any suitable usual construction and forming no part of the present invention. The drawing shows a portion of the right hand end of the usual lay beam 1 which is fixed to the front face of a sword 2. The lay beam carries a reed 3 and a shuttle box indicated generally at 4. The shuttle box includes a front box plate 5 and a back box plate the outer end 6 of which is fixed to the lay beam as by means of bolt 7. The back box plate is provided with a shuttle guiding surface which must

be accurately aligned with the reed as is well known in the art.

The particular back box plate shown is constructed of two separate members, the outer end or member 6 and the inner end or member 8, which carries the shuttle guiding surface 9. The two members may be connected together by a universal joint indicated generally at 10 and more fully disclosed in patent to W. I. Stimpson No. 1,848,674 granted March 8, 1932.

The universal joint permits the inner end or shuttle guiding member 8 to be adjusted about different axes, one extending horizontally longitudinally of the lay and shuttle box and the other 15 extending vertically. Thus the shuttle guiding member 8, carrying the shuttle guiding surface 9, may be tilted about a horizontal axis to bring the shuttle guiding surface into a plane parallel with the reed and may be moved bodily forwardly or rearwardly transversely of the lay beam to bring the shuttle guiding surface into horizontal alignment with the reed.

The inner end or member 8 of the back box plate is attached to the sword 2 by means which 25 can be manipulated to produce the desired adjustment of the shuttle guiding surface, the member being firmly fixed in position after the adjustment is accomplished.

Such adjusting means may comprise a wedge shaped member 11 positioned between the sword 2 and the member 8 of the back box plate. Member 11 may be adjustably connected to member 8 by a plurality of adjusting screws, in the drawing three such screws 12, 13 and 14 are shown. 35 Each of screws 12, 13 and 14 is left hand threaded on the end that screws into member 11 and right hand threaded on the end that screws into member 8. The ends of the screws in member 8 are slotted to facilitate adjustment. Screw 12 is 40 located above, screw 13 is located below and screw 14 is located substantially on the longitudinal center line of member 8. Thus by adjusting screws 12, 13 and 14 the box plate member 8 may 45 be bodily moved toward and from member 11 and may be tilted about a horizontal axis extending longitudinally of the lay.

The wedge shaped member 11 has an opening 15 therein for the reception of a boss 16 formed on the box plate member 8. The wedge shaped member 11 may have fitting strips which bear 50 against the sword, three such strips 17, 18 and 19 are shown on the drawing.

Fastening means are provided for fastening the members 8 and 11 to the sword 2. Such fastening means may comprise a threaded member

or cap screw 20. Cap screw 20 extends through a vertically elongated opening 21 in the sword 2, through the opening 15 in member 11 and is threaded into the boss 16 on member 8. By means of cap screw 20 the members 8 and 11 may be moved bodily transversely of the lay beam towards and from the sword 2.

The operation of the device is as follows:

To turn the member 8 about a horizontal axis to bring the shuttle guiding surface 9 into a plane parallel with the reed, the cap screw 20 is loosened and by properly adjusting screws 12, 13 and 14 member 8 is angularly adjusted relative to member 11 so that when the assembly is clamped against the sword 2 by tightening the cap screw 20 the shuttle guiding surface 9 is in a plane parallel with the reed. To move the shuttle guiding surface bodily to bring the shuttle guiding surface into horizontal alignment with the reed, the cap screw 20 and screws 12, 13 and 14 are adjusted to give the member 8 the required movement.

Having thus fully disclosed the preferred embodiment of my invention; I claim:

1. In a loom, a lay including a reed and a shuttle box having a shuttle guiding member adapted to be aligned with the reed, a sword for supporting said lay and to which said shuttle guiding member is adjustably attached, a plate positioned between said sword and said shuttle guiding member, threaded means adjustably connecting said shuttle guiding member to said plate, said means being so constructed and arranged as to provide bodily movement of said shuttle guiding member toward and from said plate and tilting movement of said shuttle guiding member about a horizontal axis extending longitudinally of the lay and means for locking said shuttle guiding member in adjusted position.

2. In a loom, a lay having a reed along which a shuttle may run, a shuttle guiding member independent of the reed supported by said lay, a member for supporting said lay and to which said shuttle guiding member is adjustably attached, a plate positioned between said members, threaded means adjustably connecting said plate to one of said members, said means being so constructed and arranged as to provide bodily movement of said shuttle guiding member towards and from said supporting member and a tilting movement of said shuttle guiding member about a horizontal axis extending longitudinally of the lay and means for locking said plate and said members together.

3. In a loom, a lay including a reed and a shuttle box having a back box plate adapted to be aligned with the reed, a sword for supporting said lay, said sword having an opening therein, a member positioned between said sword and said back box plate, said member having an opening therein aligned with said opening in said sword, a plurality of adjustable screws threaded into said back box plate and said mem-

ber, the ends of said screws engaging said back box plate having a right hand thread and the ends of said screws engaging said member having a left hand thread whereby the angular relation of said back box plate to the vertical is adjustable and threaded means extending through said openings in said sword and said member and threaded into said back box plate for moving said back box plate and said member transversely of the lay.

4. In a loom, a lay having a reed along which a shuttle may run, a shuttle guiding member independent of the reed supported by said lay, a member for supporting said lay and to which said first named member is adjustably attached, a plate positioned between said members, said plate having an opening therein, means adjustably connecting said shuttle guiding member to said plate whereby said shuttle guiding member may be tilted about a horizontal axis and brought into the same vertical plane as the reed, and fastening means extending through said opening in said plate for adjustably connecting said shuttle guiding member to said supporting member whereby said shuttle guiding member and said plate may be moved bodily transversely of said lay to thereby bring said shuttle guiding member into horizontal alignment with said reed.

5. In a loom, a lay including a reed and a shuttle box having a back box plate adapted to be aligned with the reed, a sword for supporting said lay, said sword having an opening therein, a member positioned between said sword and said back box plate, said member having an opening therein, a cap screw extending through said openings in said sword and said member and threaded into said back box plate, a plurality of adjusting screws connecting said back box plate to said member, at least one of said adjusting screws being located above said cap screw and at least one of said adjusting screws being located below said cap screw, said adjusting screws being right hand threaded into said back box plate and left hand threaded into said member, whereby said back box plate may be moved transversely of the lay and tilted about a horizontal axis extending longitudinally of the lay.

6. In a loom, a lay having a reed, a shuttle guiding member supported by said lay, a member for supporting said lay and to which said first named member is adjustably attached, a plate positioned between said shuttle guiding member and said supporting member in adjustable relationship to each, means adjustably connecting said shuttle guiding member to said plate for moving said shuttle guiding member transversely of the lay and tilting same about a horizontal axis extending longitudinally of the lay and means for locking said shuttle guiding member to said supporting member in adjusted position.

CARL D. BROWN.
